UNITED STATES PATENT OFFICE.

PATRICK J. DEVER, OF FREELAND, PENNSYLVANIA.

SHOE-SOLING TOOL.

Application filed September 5, 1922. Serial No. 586,277.

To all whom it may concern:

Be it known that I, PATRICK J. DEVER, a citizen of the United States, residing at Freeland, in the county of Luzerne and State 5 of Pennsylvania, have invented a new and useful Shoe-Soling Tool, of which the following is a specification.

This invention relates to shoemakers' tools and more particularly to a tool for use in 10 soling shoes.

The object of the invention is to provide a simple and efficient tool for nailing soles to 15 shoes.

Another object is to so construct such a 20 tool that while a nail is being driven into the sole of the shoe, a hole is being punched for the next succeeding nail.

Another object is to provide a tool of this 25 character which insures perfect alinement of the nailing.

Still another object is to so construct a tool of this character that a shoe soled thereby will have all the smoothness and comforts of a sewed shoe.

25 With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

30 In the accompanying drawings:—

Figure 1 represents a side elevation of a 35 tool constructed in accordance with this invention.

Fig. 2 is a top plan view thereof, and

40 Fig. 3 is a transverse section taken on the line 3—3 of Fig. 2.

In the embodiment illustrated, the tool 45 constituting this invention is composed of pivotally connected members 1, and 2 carrying jaws 3 and 4 at their front ends and handles 5 and 6 at the rear of the pivot which connects them. The upper jaw 3 has its inner face corrugated or serrated as shown at 50 7 to form a crimper, while the lower jaw 4, is as shown clearly in Fig. 2 of a width greater than jaw 3, being provided with a nail pulling notch 8 in its edge beyond jaw 3 as is shown clearly in Fig. 2.

Carried by the upper jaw 3 are a nail 55 driving element 9 and a punch 10 spaced

laterally from each other and arranged one slightly in advance of the other, the punch 10 being in advance of the driver 9 so that when the driver 9 is operating to force a nail into a shoe sole, punch 10 will be forming a hole in the sole for the reception of the succeeding nail.

The punch 10 and nail driver 9 are here shown provided with threaded shanks 9^a and 10^a respectively which operate through 60 threaded bores in the jaw 3 and are designed to be adjusted therein, being equipped at their outer ends with finger grips or heads 9^b and 10^b to facilitate the adjustment of these members in the jaw 3. 70

From the above description it will be obvious that the sole to be secured is placed between the jaws 3 and 4 and by forcibly closing the jaws through means of the handles 5 and 6, the nail driver will engage and force 75 in the nail for securing the shoe sole while the punch 10 will form adjacent said driven nail an opening to receive the next nail. This punch and nail driver are so arranged that the nails applied by the tool will be 80 spaced uniform distances apart and the punch point will prevent the nail driver from slipping off the head of the nail when being forced into the sole of the shoe. The beveled lower jaw insures perfect alinement 85 of the nail and the lower jaw also acts as a nail clinching device and gives to the sole of the shoe its original form.

By the use of this tool as herein described, 90 a shoe can be soled by nailing without destroying the comforts which go with the sewed shoe since the nails do not enter the inner sole and are simply forced through the outer sole and clinch in the welt on the outside of the shoe, at the same time the head of the nail is counter-sunk thus giving the shoe 95 the same smoothness that is possessed by a sewed shoe.

The handle members 5 and 6 are preferably provided at their free ends with finishing elements 11 and 12. 100

I claim:—

1. A tool of the class described comprising pivotally connected members having jaws at one end and handles at the other, 105 one of said jaws being provided with transversely spaced punching and nailing elements, the punching elements being arranged slightly in advance of the nailing element, said elements being adjustably 110

mounted in said jaw, the inner face of said jaw being serrated to form a crimping element.

2. A tool of the class described comprising a pair of pivotally connected jaws arranged in superposed relation, the upper jaw having transversely spaced nailing and punching elements extending from the outer to the inner face thereof and adapted to be 10 adjusted therein, the punching element being arranged slightly in advance of the nailing element, the other jaw having its free

end beveled on its outer face and positioned to form a clinching member for the nailing element, one of said jaws having its inner 15 face serrated to form a crimper.

In testimony that I claim the foregoing as my own, I have hereto affixed my signature in the presence of two witnesses.

PATRICK J. DEVER.
